UNITED STATES PATENT OFFICE.

NORMAN KEITH REID, OF TORONTO, ONTARIO, CANADA.

OPEN-FIREPLACE DAMPER.

1,059,906.

Specification of Letters Patent.

Patented Apr. 22, 1913.

Application filed January 25, 1912. Serial No. 673,296.

To all whom it may concern:

Be it known that I, NORMAN KEITH REID, of the city of Toronto, in the county of York, in the Province of Ontario, Canada, 5 have invented certain new and useful Improvements in Open-Fireplace Dampers, of which the following is the specification.

My invention relates to improvements in open fireplace dampers and the object of the 10 invention is to devise a damper for an open fireplace which may be operated from the front outside of the chimney hearth, which can be adjusted into any position and which will stay in such position when adjusted.

15 A further object is to leave the center of the chimney free so that there is no obstruction to the draft when fully opened and at no period when partially open will it obstruct the center of draft which is more intense and has more force and when the 20 damper is closed will completely stop all draft.

A further object is to make a damper cheap to manufacture in such a form that 25 may be readily adjusted to any chimney and which consists essentially of a rectangular plate frame having an upwardly extending flange around the opening thereof, bearings located at each end of the frame and in 30 proximity to each side thereof, wing dampers journaled in the bearings to each side of the frame so as to meet over the center of the frame opening in an inclined position and a push rod extending through the breast 35 of the chimney and connected to the wing dampers so as to throw them simultaneously upwardly toward the vertical position as hereinafter more particularly explained by the following specification.

40 Figure 1, is a portion of the chimney hearth broken away and in section to exhibit my construction of damper. Fig. 2, is a sectional view through the chimney showing the damper in full. Fig. 3, is an enlarged perspective detail of the damper.

In the drawings like letters of reference indicate corresponding parts in each figure.

45 A is a portion of the chimney provided with the usual hearth opening A¹ and arch and breast A².

A³ is an opening extending through the breast above the arch.

50 B is a rectangular frame plate designed to rest at each end and at the back upon an 55 inwardly projecting portion of the masonry

of the chimney. The central opening B¹ of the plate is provided with a flange B² extending upwardly from the frame plate around the opening thereof. The flange B² is provided at each end with an upwardly 60 extending inverted V-shaped projection B⁶.

B³ and B⁴ are bearings preferably forming part of the plate frame provided with a recess B⁵.

C and C¹ are the wings of the damper 65 provided with trunnions C² designed to enter and bear in the recesses B⁵ in the bearings B³ and B⁴. The outer edge of each of the wing dampers C and C¹ bear upon the top of the flange B².

70 E is a nail or pin cast at one end in each of the bearings B³ and B⁴ to one side of the recess B⁵. The trunnions C² are inserted within the recess B⁵ and the pins or nails are bent over the trunnions C² so as to retain them in place within the recess. 75

F is a cross bar extending across the opening of the plate frame substantially centrally thereof.

F¹ is a lever pivoted centrally on the cross 80 bar F by the pin F².

C³ and C⁴ are hollow bosses cast upon the wings of the dampers C and C¹.

C⁵ and C⁶ are links pivotally connected at one end to each end of the lever F and are 85 connected at their opposite end to the wing dampers C and C¹ by pins C⁷ extending through the hollow bosses C³ and C⁴ and the links C⁵ and C⁶.

G is the slotted plate secured above the 90 arch of the chimney so that the opening thereof registers with the opening A³ extending through the arch of the chimney.

H is a push bar extending through the opening A³ of the chimney breast and an 95 opening I formed in the flange B² of the chimney damper. The push bar H is provided with ratchet notches H¹ designed to engage with the slots of the plate G. The inner end of the push bar is loosely connected by a pivot H² to the lever F¹.

100 From this description it will be seen that all that is necessary to do in adjusting the damper is to raise the push bar upwardly so as to free it from the slot of the plate G when it may be pulled outwardly to any 105 position so as to throw the wings C and C¹ of the damper upwardly toward the vertical position shown by dotted lines in Fig. 2.

110 From this description it will be seen that

I have devised a damper which may be readily adjusted from outside the chimney breast so as to leave the chimney free from obstruction and so that the center of draft 5 will not be interrupted when the damper is only partially opened.

What I claim as my invention is:

In combination with a chimney, a damper comprising a frame having bearings, longitudinally extending flanges between said 10 bearings, inverted V-shaped projections on said flanges near the ends of said frame, said projections adapted to support damper

wings, a horizontal bar extending across the frame centrally thereof, a lever pivotally connected to said cross bar intermediate its length, damper wings pivotally supported on said bearings, means for connecting said lever to said damper wings, a slotted plate, and a notched push bar extending through 15 the slot and loosely connected to said lever. 20

NORMAN KEITH REID.
